NO. 11,504

Nov 11, 1879

UNITED STATES PATENT OFFICE.

EDMUND PYNE, OF NEW YORK, N. Y., ASSIGNOR TO THE BIGELOW CARPET COMPANY, OF CLINTON, MASSACHUSETTS.

DESIGN FOR CARPET.

Specification forming part of Design No. **11,504**, dated November 11, 1879; application filed September 18, 1879.
[Term of patent 3½ years.]

To all whom it may concern:

Be it known that I, EDMUND PYNE, of New York, in the city and county of New York, have invented a new and original Design for a Carpet, of which the following is a specification.

The accompanying photographic illustration represents a face view of my newly-designed carpet.

This invention relates to a new and original design for carpets, oil-cloths, and similar fabrics, and for the border of the same.

It consists in the new ornamentation and grouping of the figures hereinafter more fully described.

In the accompanying photograph, the letter A represents the body of the carpet. B is the border of the same. Upon the background A is shown a field, a, of irregular outline, and appearing to represent a lake or small body of water. At one side of this lake a is a pavilion, b, and below the same a fence, c. Above the roof of the pavilion b is a rich bouquet, d. The lower portion of the pavilion b and a portion of the fence c are partly concealed by a floral group, e. The field a is further surrounded by a profusion of flowers and leaves, f, as shown. Below the fence c is a zigzag bar, g, from which is suspended a flower-bas-

ket, h, containing series of flowers i i and leaves j, and having a handle, l.

The border B is by an irregular bar divided into two stripes. The inner stripe contains a substantial reproduction of the flower-basket h and its flowers i, leaves j, and handle l. The outer stripe is ornamented by disconnected groups of flowers and leaves, as shown.

I claim—

1. The design for a carpet, consisting of the field a and pavilion b, substantially as shown.
2. The design for a carpet, consisting of the field a, pavilion b, fence c, bouquet d, and group e, substantially as shown.
3. The design for a carpet, consisting of the field a, bouquet d, and group e and f, substantially as shown.
4. The design for a carpet, consisting of the bar g and flower-basket h, substantially as shown.
5. The design for a carpet, consisting of the figures h, i, j, and l, substantially as shown.
6. The design for a carpet, consisting of the figures a, b, c, d, e, f, g, and h, substantially as shown.

EDMUND PYNE.
